UNITED STATES PATENT OFFICE.

JOHN W. DAVIS, OF ST. CLAIR, MISSOURI, ASSIGNOR OF ONE-FOURTH TO CHARLES F. BRIEGLER, OF ST. CLAIR, MISSOURI.

TRANSFORMER OF ELECTRICITY.

1,056,739.

Specification of Letters Patent. Patented Mar. 18, 1913.

Application filed May 8, 1911. Serial No. 625,847.

To all whom it may concern:

Be it known that I, JOHN W. DAVIS, a citizen of the United States, and a resident of St. Clair, State of Missouri, have invented a certain new and useful Improvement in Transformers of Electricity, of which the following is a full, clear, and exact description, reference being had to the accompanying drawing, forming a part hereof.

10 My invention relates to an improvement in commutators, and consists of the novel arrangement and construction of parts as set forth in this specification and in the claims.

15 The object of my invention is to construct a device which may be used either to change a direct to an alternating current, or an alternating to a direct current.

20 My improved commutator is more simple in its construction, less expensive and far more durable than any form of commutators now in use.

25 Referring to the drawings: Figure 1.— is a plan view of the commutator of my invention, showing its mountings, contacts and motor. Fig. 2.— is an elevation of the commutator forming part of my invention. Fig. 3.— is another elevation of the commutator forming part of my invention. Fig. 4.— is 30 an end elevation of the commutator showing a modified form of my invention with the roller brushes in contact.

1 represents a base, having a frame 2 and a motor 3 mounted thereon. Mounted for 35 rotation in suitable bearings 4—4 on the frame 2 is the shaft 5. Mounted upon the shaft 5 and insulated therefrom and from each other are a plurality of segments 6—6 and 7—7. Rigidly mounted upon the upper 40 part of the frame 2, insulated therefrom and positioned to contact with the segments 6—6 and 7—7 are the brushes 8^a—8^b. Mounted upon the lower side of said frame 2 on the side of the frame opposite to the brushes 45 8^a—8^b, insulated therefrom and positioned to contact with segments 6—6 and 7—7 are the brushes 9^a—9^b.

50 The current is carried into my commutator by the wires 10—10 which are held in position against the brushes 8^a—8^b by the binding screws 11—11 and the commutated current is carried from my device by the wires 10^a—10^b which are held in position against the brushes 9^a—9^b by the binding screws 11^a—11^b.

Rigidly mounted on one end of the shaft 5 is the gear-wheel 12, which is positioned to mesh with the fixedly mounted gear wheel 13 upon the motor shaft 14.

5 In a modified form of my construction the 60 brushes 8^a—8^b—9^a—9^b have a roller 15 mounted for rotation upon their free end and positioned to contact with the segment 6—6 and 7—7.

The operation of my device is as follows: 65 When it is desired to change a direct to an alternating current the current is carried into my device by means of the wires 10—10 and motion imparted to the shaft 5 by means of the gear-wheels 12 and 13 and the motor 70 3. The segments 6—6 are so constructed in form and so positioned on the shaft 5 that when the brushes 8^a—8^b are in contact therewith the current passes directly through said segments to the companion brushes 9^a—9^b; 75 while the segments 7—7 are so constructed in form and so positioned on the shaft 5 that when the brushes 8^a—8^b are in contact therewith the current passes through said segments from the brush 8^a to the brush 9^b and 80 from the brush 8^b to the brush 9^a. The revolution of the shaft 5 causes the segments to revolve and the segments 6—6 and 7—7 are successively brought into contact with the brushes 8^a—8^b and 9^a—9^b and the current passes from my device through the brushes 9^a—9^b and the wires 10^a—10^b has an alternating current, the frequency of alternation being controlled by the frequency of revolution of the shaft 5 and the speed 90 of the shaft is regulated by any suitable gearing or by a rheostat attached to the motor. If the change is to be made from an alternating to a direct current the alternating current is carried into my device 95 through the wires 10—10 and the operation of my commutator is the same as above described for commutating the direct current.

Obviously, the mechanism admits of considerable modification without departing 100 from this invention, and therefore I do not wish to be limited to the specific construction and arrangement shown.

Having thus described my invention I claim:

1. In a device of the class described, a shaft, two segments mounted on said shaft, and insulated therefrom and from each other, each of said segments consisting of a central member extending circumferentially 110

of the shaft and oppositely disposed end members extending axially of the shaft, the respective members of each segment being in alinement with corresponding members on the other segment, and means for rotating said shaft.

2. In a device of the class described, a shaft, two segments mounted on said shaft and insulated therefrom and from each other, each of said segments consisting of a central member extending circumferentially of the shaft and oppositely disposed end members extending axially of the shaft, the respective members of each segment being in alinement with corresponding members on the other segment, two brushes positioned to contact with said segments and to carry an electric current into said segments and to the commutated current away from same, and means for rotating said shaft.

3. In a device of the class described, a shaft, two segments mounted on said shaft,

and insulated therefrom and from each other, each of said segments consisting of a central member extending circumferentially of the shaft and oppositely disposed end members extending axially of the shaft; the 25 respective members of each segment being in alinement with corresponding members on the other segment, two brushes positioned to contact with said segments and to carry an electric current into said segments and 30 the commutated current away from same, and means for rotating said shaft.

In testimony whereof I have signed my name to this specification in the presence of two subscribing witnesses.

JOHN W. DAVIS.
